[57] ABSTRACT

A flying shear, adapted to be installed in the shearing line at the finished end of the heavy plate rolling mill plant for shearing metal plates in various lengths, having a stationary outer housing mounted on the bed plates, a pair of upper knife holder drives which are mounted on the outer housing and drive an eccentric cam shaft journaled on the outer housing for lifting and lowering an upper knife holder, a shiftable inner shear housing moving parallel to the traveling stock and being disposed inside of the outer housing, the inner shear housing guiding the liftable upper knife holder and carrying a lower knife holder to effect a shearing action between the upper knife holder, a pair of shifting supports bearing on the outer housing for supporting the inner shear housing, and a pair of shifting drives mounted on the bed plates for reciprocating the inner shear housing in synchronism with the traveling stock at the time of cutting. The upper knife holder is adapted to reciprocate both elevationally and laterally, and is connected to the eccentric cam shaft for rotating the output shaft of the upper knife holder driving device that is arranged in a stationary manner by a connecting rod. Thus, the desired sectional length of stock is provided by the simple structure of the flying shear.

FIG. 29

FLYING SHEAR FOR CUTTING STOCK INTO DESIRED SECTIONAL LENGTHS

BACKGROUND OF THE INVENTION

This invention relates to a flying shear for cutting stock into desired sectional lengths while in motion, and more particularly to a crosscut dividing shear or so called "end shear" installed in a shearing line at the finishing end of the heavy plate rolling mill plant required for heavier shearing force for cutting the wider and thicker plates and for higher shearing speed corresponding to the rolling productivity of the plate mill so as to provide advantageous effects.

The layout of the conventional shearing line at the finishing end of the heavy plate rolling mill plant, as shown with respect to one example of typical type in FIG. 1, consists of mill line runout roller tables 101, cooling beds 102 and 103, cooling bed delivery roller tables 104 and 105, shearing line roller tables 106 and 107, stationary crop shears 108 and 109, rotary knife side trimming shears with scrap choppers 110, flat knife side trimming shears 111, stationary trimming shears 112, stationary crosscut dividing shears 113, shearing line runout roller tables 114 and 115 and piling devices 116 and 117. Thus, only the stationary arranged shears have been installed heretofore for the crop cut and crosscut dividing.

In crop cut and crosscut dividing, the stocks supplied on the shearing line roller tables are stopped every time the shearing takes place, and must be accelerated again on the roller tables after the completion of the shearing. The down time of the duration of the stop and start of the stock thus taking place is not acceptable in a heavy plate rolling mill plant where high productivity is required. At present, the lack of rolling capacity of the heavy plate rolling mill of the dividing shearing treating capacity in the stationary arranged crosscut dividing shear particularly becomes one bottleneck for enhancing the production capacity of the heavy plate plant. In order to overcome this problem, as shown in FIG. 1, one row of shearing line is added to one rolling line so as to provide two rows of shearing lines in the respective heavy plate plant.

However, in the heavy plate rolling mill plants required for high productivity to be constructed in the future, the fact that at least two rows of shearing line must be installed, owing to the lack of the crosscut dividing treating productivity of the stationary arranged shears, means an increase in the finishing equipment, finishing yarn and building area, and causes a bottleneck from the viewpoint of reducing the building expense of a heavy plate plant.

For such reasons, it is proposed to adopt a flying shear disclosed in the embodiments of this invention on a finishing line of heavy plate mill. FIG. 2 shows one example of the layout conducted for crosscut dividing in the shearing line at the finishing end of the heavy plate rolling mill plant with a flying shear of this invention. This example, shown in FIG. 2, will now be described generally. It is composed of mill line runout roller tables 201, cooling beds 202 broader in width for a rolled stock longer than heretofore required for the improvement of the rolling productivity and yield, cooling bed delivery roller tables 203, shearing line roller tables 204, stationary crop shear 205 disposed nearer the cooling beds 202, rotary knife side trimming shears 206

with scrap choppers enabling side trimming continuously in high speed even for heavy stock for the layout of the flying shears, and flying crosscut dividing shear 210 of one embodiment of this invention having stock feeding pinch rolls 207, stock feeding length measuring rolls 208 and photoelectric relay 209 for detecting the front end of the stock at the first cut, shearing line runout roller tables 211, and piling devices 212 for operating in high speed corresponding to the shearing speed of the flying shears.

It is confirmed that most conventional systems have a great deal of disadvantages when trying to adopt the conventional flying shearing system of the various types of the flying shears used in the shear line for heavy plate as composed in FIG. 2. There exist several conventional flying shears for shearing hot and cold rolled strip, such as the rotary drum type as shown in FIG. 3(a), pendulum or rocker type as shown in FIG. 3(c), flying press type or so called die cut shear as shown in FIG. 3(d) and hot rolled billet and bar, such as rotary-crank type as shown in FIG. 3(b), but since each of these types, except the die cut type, so operate that its knife edge moves in a circle or approximately arcuately, a forward component of the shear knife speed parallel with the continuously traveling material to be cut is not constant theoretically at the time of cutting. For this reason, the knife edge life is reduced, and the shock stress throughout the machine is increased to cause a serious inconvenience to shear the heavy plate. Since the angle formed with the stock and the top and bottom knife varies during cutting in the rotary drum type and pendulum type, it has the disadvantage that the cut surface of the stock becomes sharp at its ends and, accordingly, is not proper for the cutting of heavy plate required for the right angle of the cut surface of the stock.

As to this point, since the angle formed with the stock and the top and bottom knife of the die cut shear is constant, so that the motion of bottom knife is parallel with the traveling material, the aforementioned disadvantage is overcome. However, it introduces the increase of the weight of the machine and increase of inertia force of mass that the conventional die cut shear is scaled up so as to apply it to the one required for the heavy shearing force, such as shearing of heavy plate, with the result that the body, driving device and capacity of an electric motor become great so that its manufacturing expense becomes very high as its disadvantage. Further, the conventional flying shear for hot or cold rolled strip for repeating shearing in a desired constant length of shearing, and when the desired length of shearing is varied, the operation of machine is once stopped so that after the changing of step gearing, mis-cut gearing, and synchronizing adjustment, and adjustment of gear ratio of the stepless transmission, the operation is restarted, and this becomes a serious disadvantage when it is required to cut in various desired length of shearing in every cut or every several cuts such as the finishing line of heavy plate mill. Then, in the conventional die cut shear, in order to support the shifting shear housing, the wear plates are used on the sliding surface, or cylindrical rollers are used. Therefore, it introduces an inconvenience from the viewpoint of a scale problem and heavy wear to apply this to the flying shear for heavy plate required for high speed and heavy shearing force.

SUMMARY OF THE INVENTION

This invention contemplates the elimination of the aforementioned disadvantages of the conventional flying shear, and the provision of a novel and improved flying shear for cutting the stock into desired sectional lengths in motion.

It is, therefore, an object of this invention to provide a flying shear for cutting the stock into desired sectional lengths which is simple in structure by reducing the weight of the reciprocally flying portions and its inertia.

It is another object of this invention to provide a flying shear for cutting the stock into desired sectional lengths which eliminates the wear of the sliding portions, engagement of scale, unbalanced contact and seizure so as to provide a stable operation with long life with less power consumption.

It is a further object of this invention to provide a flying shear for cutting the stock into desired sectional lengths which is easy to manufacture and is designed for enduring high speed and heavy load with constant speed in high accuracy.

It is still another object of this invention to provide a flying shear for cutting the stock into desired sectional lengths which reduces acceleration with compact structure with less fluctuation of torque for accurate control.

It is still another object of this invention to provide a flying shear for cutting the stock into desired sectional lengths which provides an accurate length of shearing.

It is still another object of this invention to provide a flying shear for cutting the stock into desired sectional lengths which may vary the length of shearing without stopping the operation of the shear and may also cut pieces continuously with high accuracy.

According to one aspect of this invention, there is provided a flying shear installed in the shearing line at the finished end of the heavy plate rolling mill plant for shearing metal plates in various lengths having a stationary outer housing mounted on the bed plates, a pair of upper knife holder drives which are mounted on the outer housing and drive an eccentric cam shaft journaled on the outer housing for lifting and lowering an upper knife holder, a shiftable inner shear housing moving parallel to the traveling stock, being inside of the outer housing and guiding the liftable upper knife holder and carrying a lower knife holder to effect a shearing action between the upper knife holder, a pair of shifting supports beared on the outer housing for supporting the inner shear housing, and a pair of shifting drives mounted on the bed plates for reciprocating the inner shear housing in synchronism with the traveling stock at the time of cutting, characterized in that the upper knife holder is adapted to reciprocate both elevationally and laterally and is connected to the eccentric cam shaft for rotating as the output shaft of the upper knife holder driving device that is arranged in a stationary manner by a connecting rod.

Another characteristic feature of the flying shear of this invention is that the lower knife holder is mounted opposite to the upper knife holder, two pairs of cranks are rotatably secured pivotally at the respective portions, laterally and longitudinally, on the cross beam at the outer housing and at a plurality of portions of the shear housing reciprocating laterally, and are rotatably

supported at the upper end of the cross link inserted at the lower front and rear portions on the crank pins of the cranks.

A further characteristic feature of the flying shear of this invention is that the inner eccentric cam is fixed to the drive shaft for one-way rotation, the outer eccentric cam movably engaged with the outer periphery of the inner eccentric cam is so mounted as to inversely drive with the same speed from the inner eccentric cam at the same time the connecting rod, movably engaged with the outer periphery of said outer eccentric cam, is connected directly or through a rockable lever to the flying shear housing, whereby the composite motion of the inner and outer eccentric cams are converted to the reciprocating motion of the knife holder.

Still another characteristic feature of the flying shear of this invention is that the flying shear comprises a knife holder reciprocating flying drive device for producing constant speed portions of the back and forth strokes of the knife holder wherein the operation starting point of the knife holder is provided at the start point of the constant speed section of the back stroke and the knife holder reciprocating flying drive motor is operated intermittently.

Another characteristic feature of the flying shear of this invention is that the upper knife holder drive device and the inside shearing housing reciprocating drive device are driven separately by an electric motor and the upper knife holder drive motor is operated intermittently and the rotating speed of the eccentric cam shaft for the upper knife edge drive is rotated in higher speed than the rotating speed of the inner and outer eccentric cam shafts for the inside shearing housing reciprocating flying drive.

Still another characteristic feature of the flying shear of this invention is that the inside shearing housing reciprocating flying drive motor is operated in variable speed, linearly varying with the feeding speed of the stock as a standard, when the feeding speed of the stock is constant with sufficient time from the time when the shearing is completed, so that the upper knife is separated from the stock before the time when the next shearing operation is started, so as to obtain the shearing length, except the basic shearing length obtained when the inside shearing housing reciprocating flying drive motor is continuously operated at constant speed and the shearing length obtained when the inside shearing housing reciprocating flying drive motor is intermittently operated.

BRIEF DESCRIPTION OF THE DRAWINGS

Further objects, features and advantages of this invention will become apparent from the following description taken in conjunction with the accompanying drawings, in which:

DESCRIPTION OF THE PREFERRED EMBODIMENTS

The embodiments of the present invention will now be described by briefly dividing into the essential parts as a stationary outer housing 10, upper knife holder drive 20, shiftable inner shear housing 30, shifting supports 40 and shifting drive 50 for inner shear housing with reference to FIGS. 4 to 6.

Stationary Outer Housing 10

Two frames 12 and 12' mounted on the bed plates 11 are connected by top cross beams 13 and 13' and bottom cross beams 14 so as to form an outer housing 10.

Upper Knife Holder Drive 20

An upper knife holder drive motor 22 and 22', and gear reducer 23 and 23' are mounted on the drive bases 21 and 21' provided on the two frames 12 and 12' so as to rotate an eccentric cam shaft 24 journaled on the top cross beams 13 and 13' with the timing and cycle corresponding to the desired cutting lengths to give an upper knife holder 26 supported by pitmen 25 and 25' with up and down motion. The upper knife holder 26 carries the upper shear blade 27 thereunder.

Shiftable Inner Shear Housing 30

The upper portions of the left and right frames 31 and 31' are connected by front and back cross beams 32 and 33 for guiding to support the upper knife holder 26, and the lower portions thereof are connected by the lower knife holder 34 to form an inner shear housing 30.

The lower knife holder 34 carries the lower shear blade 35 opposite to the upper shear blade 27 at the upper portion thereof. The inner housing 30 is inside the outer housing 10, and is carried by shifting supports 40 as will be hereinafter described and is given by a reciprocatory motion, so called flying motion, parallel with the stock to be cut with the timing and cycle corresponding to the desired cutting lengths by shifting drive for inner shear housing 50 as will be hereinafter described.

Shifting Supports 40

Four pairs of shifting supports 40 carry two frames 31 and 31' and lower knife holder 34 of the inner housing 30 by the respective pins 41. The pin 41 is journaled on the upper portion of T-type link 42. The lower portion of the T-type link 42 is beared with crank pins 44 and 44' of two pairs of crank 43 and 43' at the front and rear portions.

The crank shafts 45 and 45' of the crank 43 and 43' are journaled by the bottom cross beam 14. Thus, the mechanism composed of the T-type link 42 and two pairs of cranks 43 and 43' is generally called Roberts' mechanism, but as shown in FIG. 7, assuming that

$$a/d = 0.584, b/d = 0.593, l/d = 1.112$$

wherein

a = center distance between crank pin 44 and crank shaft 45,

b = center distance between crank pin 44' and crank shaft 45',

b = center distance between two crank pins 44 and 44' at T-type link 42,

l = height of T-type link 42 (vertical distance from center of pin 41 to connecting line of crank pins 44 and 44'), and

d = center distance between two crank shafts 45 and 45' at bottom cross beam 14, the center of pin 41 may approximately move linearly.

In the embodiment, as shown in FIG. 7, assuming that

$$a = 788 \text{ mm}, b = 800 \text{ mm}, l = 1500 \text{ mm}, \text{ and } d = 1349 \text{ mm},$$

actual deviation may be ignored in the range of approximately 1240 mm of reciprocatory flying stroke so as to provide a linear motion.

Shifting Drive for Inner Shear Housing 50

The fact that the shear shown as the embodiment of this invention is called flying type means that the shear blades 27 and 35, respectively carried on the upper knife holder and lower knife holder 26 and 34, are moved in synchronism with the stock fed continuously at the times of their shear actions on the stock. For permitting this purpose, the upper knife holder 26 is supported by the pitmen 25 and 25'. The inner shear housing 30 for carrying the lower knife holder 34 and for guiding the upper knife holder 26 is supported by the shifting supports 40 and is moved by the shifting drive for inner shear housing 50.

Then this will now be described with reference to FIGS. 4, 8 and 9. This movement is transmitted by connecting rods 52 and 52' for connecting between the pivoted connections 51 and 51' and the pivoted connections 53 and 53' of the end of the pendulum levers 54 and 54'.

The pendulum levers 54 and 54' are swung by straps 57 and 57' for connecting between the pivoted connections 55 and 55' and pairs of eccentrics 58-59 and 58'-59' at the pivoted connections 56 and 56' mounted on the bed plates 11 as a center. Here, numerals 58 and 58' illustrate inner eccentrics, and 59 and 59' outer eccentrics. The inner eccentrics 58 and 58' are mounted on the shafts 60 and 60', respectively, and rotated in one way. The outer eccentrics 59 and 59' are rotated opposite to the inner eccentrics 58 and 58' around the outer periphery of the inner eccentrics 58 and 58' with the same rotating speed.

Crank pins 61 and 61' for carrying sliding blocks 62 and 62' are mounted on the outer eccentrics 59 and 59' rotatable around the outer periphery of the inner eccentrics 58 and 58', and the sliding blocks 62 and 62' are received in radial slots 63 and 63' on the adjacent end faces of gears 64 and 64', respectively, which presently are freely turnable on sleeves 65 and 65', respectively on the shafts 60 and 60'.

The gears 64 and 64', which are of the same pitch diameter, are in permanent mesh with identical gears 66 and 66', respectively, of the same pitch diameters on counter shaft 67. The shafts 60 and 60' and counter shaft 67 are coupled to output shafts 68 and 68', 69 and 69', respectively, and gears 70 and 70', 71 and 71', which are of the same pitch diameter, are mounted to the output shafts 68 and 68', 69 and 69', respectively, to be meshed with pinions 72 and 72', respectively. The pinions 72 and 72', which are of the same pitch diameter, are driven by motors 76 and 76', 77 and 77', of the same rotating speed, through the pinions 74 and 74', 75 and 75', of the same pitch diameters, meshed with gears 73 and 73', of the same pitch diameters. The inner eccentrics 58 and 58' and outer eccentrics 59 and 59' thus constructed are rotated in the same rotating speed in opposite direction to each other. As a result, a reciprocatory motion having once approximate constant section on one forth stroke and also once

approximate constant speed section on one back stroke of the inner shear housing 30 per one revolution of the inner and outer eccentrics 58 and 58', 59 and 59' in the constant speed rotation of the motors 76 and 76', 77 and 77'. The speed of the inner shear housing 30 of the constant speed section of this forth stroke is synchronized with the feeding speed of the stock so that so called flying shear action composed of the contacting of the upper shear blade with the stock, cutting action by the upper and lower shear blades and leaving of the upper shear blade from the stock is conducted. The movement x of the inner shear housing 30 takes place due to the composite motion of the inner and outer eccentrics 58 and 58', 59 and 59', represented approximately by the following formulae of the mechanism as shown in FIG. 10:

$$x = f(\theta) = L/l [e_1 + e_2 - e_1 \cos \theta - e_2 \sqrt{1 - (e_1/k \sin 2\theta)^2} \cos \theta + (e_1 e_2/k) \sin \theta \cdot \sin 2\theta] \quad (1)$$

$$dx/d\theta = d/d\theta f(\theta) \approx L/l [e_1 \sin \theta + e_2 \sqrt{1 - (e_1/k \sin 2\theta)^2} \sin \theta + (2e_2 (e_1/k)^2 \sin 2\theta \cos 2\theta \cos \theta / \sqrt{1 - (e_1/k \sin 2\theta)^2}) + (e_1 e_2/k) \cos \theta \sin 2\theta + (2e_1 e_2/k) \sin \theta \cdot \cos 2\theta] \quad (2)$$

wherein

e_1 : (mm) eccentricity of inner eccentrics 58 and 58',

e_2 : (mm) eccentricity of outer eccentrics 59 and 59',

k : (mm) distance between center of crank pins 61 and 61' turning center of outer eccentrics 59 and 59',

L : (mm) center distance between pivoted connections 53 and 53', 56 and 56' in the pendulum levers 54 and 54',

l : (mm) center distance between pivoted connections 55 and 55', 56 and 56' in pendulum levers 54 and 54',

L/l : lever ratio of the pendulum levers 54 and 54',

x : (mm) movement of the inner shear housing 30,

θ : (radian) rotary angle of inner eccentrics 58 and 58',

ϕ : (degrees^o) rotary angle of inner eccentrics 58 and 58',

$$\theta = (\pi/180)\phi \quad (3)$$

$dx/d\theta$: (mm/rad) movement character per rotating angle,

$dx/d\phi$: (mm/^o) movement character per rotating angle,

$$dx/d\theta = \pi/180 \cdot dx/d\phi \quad (4)$$

On the one hand, the formula $dx/d\theta = d/d\theta f(\theta)$ is solved in the sections of $45^\circ - 90^\circ - 135^\circ$ and $225^\circ - 270^\circ - 315^\circ$ from the formula (2),

at $\phi = 45^\circ$: $dx/d\theta = L/l \sqrt{2} [e_1 + e_2 \sqrt{1 - (e_1/k)^2} + e_1 e_2/k]$ 55 (3)

at $\phi = 90^\circ$: $dx/d\theta = L/l [e_1 + e_2 - 2e_1 e_2/k]$ (4)

at $\phi = 135^\circ$: $dx/d\theta = L/l \sqrt{2} [e_1 + e_2 \sqrt{1 - (e_1/k)^2} + e_1 e_2/k]$ (5)

at $\phi = 225^\circ$: $dx/d\theta = -L/l \sqrt{2} [e_1 + e_2 \sqrt{1 - (e_1/k)^2} + e_1 e_2/k]$ (6)

at $\phi = 270^\circ$: $dx/d\theta = -L/l [e_1 + e_2 - 2e_1 e_2/k]$ (7)

at $\phi = 315^\circ$: $dx/d\theta = -L/l \sqrt{2} [e_1 + e_2 \sqrt{1 - (e_1/k)^2} + e_1 e_2/k]$ (8)

In the embodiment of this invention, since the section of $\phi = 45^\circ - 90^\circ - 135^\circ$ is the synchronizing section of

the inner shear housing 30 and feeding stock, at least the following formula must be consistent:

$$(d/d\phi)f(45^\circ) = (d/d\phi)f(90^\circ) = (d/d\phi)f(135^\circ).$$

If thus consistent, as clear from the formulae (3) to (8), the following formula is consistent:

$$(d/d\phi)f(225^\circ) = (d/d\phi)f(270^\circ) = (d/d\phi)f(315^\circ).$$

Accordingly, the following conditions are consistent from the formulae (3) to (8):

$$1/\sqrt{2} [e_1 + e_2 \sqrt{1 - (e_1/k)^2} + e_1 e_2/k] = e_1 + e_2 - 2e_1 e_2/k \quad (9)$$

Now, assuming that the following conditions are existent, and the formulae (10) and (11) are substituted to the formula (9),

$$a = e_2/e_1, e_2 = ae_1 \quad (10)$$

$$b = k/e_1, k = be_1 \quad (11)$$

$$a = b(\sqrt{2} - 1)/1 + \sqrt{b^2 - 1} - (b - 2) \sqrt{2} \quad (12)$$

In the embodiment of this invention, since $b = 5.4107$ is adopted, $a = 1.5$ is derived from the formula (12).

And, $e_1 = 100$ mm is also adopted in this embodiment,

$e_2 = 150$ mm, $k = 541.07$ mm are derived from the formulae (10) and (11).

Now, the traveling speed V_s (mm/sec.) of the inner shear housing 30 is expressed by the following formula:

$$V_s = dx/dt = d\theta/dt \cdot dx/d\theta$$

$$\text{or } d\phi/dt \cdot dx/d\phi$$

$$(d\theta/dt = \pi/180 \cdot d\phi/dt)$$

$$(dx/d\theta = 180/\pi \cdot dx/d\phi) \quad (13)$$

Here, $dx/d\theta$ (mm/rad.) is obtained by the formula (2). If the feeding speed of the stock is represented by V_f (mm/sec.), in the synchronizing section $\phi = 45^\circ - 90^\circ - 135^\circ$, the following formula must be consistent:

$$V_f = V_s \quad (14)$$

Accordingly, the following formula is consistent of the synchronizing range from the formulae (13) and (14):

$$V_f = d\theta/dt \cdot dx/d\theta \text{ or } V_f = d\phi/dt \cdot dx/d\phi \quad (15)$$

If the formula

$$dx/d\theta = L/l (e_1 + e_2 - 2e_1 e_2/k)$$

is substituted from the formula (4) at $\phi = 90^\circ$, the formula (15) becomes

$$V_f = d\theta/dt \cdot L/l (e_1 + e_2 - 2e_1 e_2/k) \quad (16)$$

Then, in the continuous operation of the shifting drive motors, the rotating speed $d\theta/dt$ is constant, and the rotating angle of inner and outer eccentrics between two

consecutive cuts are $\theta = 2\pi$ or $\phi = 360^\circ$ so that the period between two consecutive cuts be tc , and if the formula (16) is integrated, the following formula (17) is obtained:

$$\int_0^{tc} Vf dt = \frac{L}{l} \left(e_1 + e_2 - \frac{2e_1 e_2}{k} \right) \int_0^{2\pi} \frac{d\theta}{dt} dt$$

$$= 2\pi \frac{L}{l} \left(e_1 + e_2 - \frac{2e_1 e_2}{k} \right) = \text{constant} \quad (17)$$

$$\int_0^{tc} Vf dt$$

of the formula (17) represents the length which would be cut at ideal synchronism by continuous operation of shifting drive motors, and assuming that this length is called hereinafter basic cutting length L_z , the formula (17) is represented as follows:

$$L_z = 2\pi L/l (e_1 + e_2 - 2e_1 e_2/k) \quad (18)$$

If the formula (18) is substituted in the formula (16), the following formula (19) is obtained:

$$V_f = d\theta/dt \cdot L_z/2\pi = d\phi/dt \cdot L_z/360 \quad (19)$$

In the embodiment of this invention, since the following conditions are consistent,

$$\begin{aligned} L_z &= 3000 \text{ mm}, \\ e_1 &= 100 \text{ mm} \\ e_2 &= 150 \text{ mm} \\ k &= 541.07 \text{ mm}, \end{aligned}$$

the following formula is obtained from the formula (18):

$$L/l = L_z/2\pi(e_1 + e_2 - 2e_1 e_2/k) = 2.454$$

The various values thus obtained are substituted in the formulae (1) and (2) and calculated by numerals, $x = f(\phi)$ and $dx/d\phi$ becomes as shown in FIGS. 11 and 12. In the embodiment of this invention, since the max. feeding speed of the stock is $V_f \text{max} = 1500 \text{ mm/sec.}$ (90 m/min.) and $L_z = 3000 \text{ mm}$, the following formula is obtained from the formula (19):

$$d\phi/dt = 360 V_f/L_z = 360 \cdot 1500/3000 = 180^\circ/\text{sec.} \quad (30)$$

R.P.M.)

Therefore, if the calculated value of $2e_1$ and $d\phi/dt$ $\frac{1}{2}^\circ/\text{sec.}$ are substituted in the formula (13) to be calculated, the traveling speed of the inner housing at continuous operation of shifting drive motors, $V_s = dx/dt$ becomes as shown in FIG. 13, the respective approximate constant speed sections are obtained in the section of $\phi = 45^\circ - 90^\circ - 135^\circ$ at the forward stroke of the reciprocating motion and the section of $\phi = 225^\circ - 270^\circ - 315^\circ$ at the backward stroke of the reciprocating motion.

As shown in FIG. 13, in the embodiment of this invention, it is possible to restrain the accuracy of the error of the constant speed by absolute value within 3 percent in high level of

$$\Delta V_s/V_s = 1540 - 1500/1500 = 0.027 < 3\%$$

Operation of the Shifting Drive Motors

Two methods are applied to the operation of the shifting drive motors of the flying shear shown in the embodiment of this invention.

One of them is a method having the steps of running continuously the shifting drive motors at constant uniform speed, and cutting repeatedly the stock in the basic cutting length of $L_z = 2\pi \cdot L/l \cdot (e_1 + e_2 - 2e_1 e_2/k)$ shown by the formula (18). In the embodiment of this invention, $L_z = 3000 \text{ mm}$ being constant. This is hereinafter called continuous operation of the shifting drive motors, and its cutting cycle diagram is shown in FIG. 14.

The other of them is a method called start and stop operation of the shifting drive motors, which is the case that the stock is flying out in the various cutting lengths longer than the basic cutting length L_z in such a manner that the shifting drive motors are started and stopped by the timing and cycle corresponding to the desired cutting lengths so as to obtain a constant or uniform speed before and after the time of cutting.

FIG. 15 shows a cutting cycle diagram of the conventional start and stop operation, and FIG. 18 shows a cutting cycle diagram of the start and stop operation in the embodiment of this invention.

Reference is now made to FIG. 15, a point 0 is the start and stop point, and the sections 0-P and y-0 are acceleration and deceleration range of the shifting drive motors. The section p-y is the constant or uniform speed range of the shifting drive motors, and the inner shear housing is synchronized with the feeding speed of the stock in the section p-y of this section to give a uniform speed so as to conduct the cutting action by the upper and lower shear blades and the leaving of upper shear blade from the stock. The change of the cutting length is conducted by varying the cutting cycle time tc shown in FIG. 15. In operation shown in FIG. 15, as shown in the example in FIG. 16, the acceleration time for shifting drive motors is considerably shorter as 0.5 second with respect to the synchronizing speed of the inner shear housing $V_s = 1.5 \text{ m/sec.}$ so that the necessary motor power becomes extremely large in case of the weight of the inner shear housing and inertia of the flying mass being large such as cutting the heavy plate so that the increase of the motor power enhances further the inertia mass of the motors and shifting drives with the result that it is difficult to make the flying shear of the heavy load and high speed into a practical use.

Then, in considering with the error of the acceleration time of the shifting drive motors, there exists a dynamic error between the actual speed of the motor and the required desired speed during the acceleration period, so that this dynamic speed error introduces the error of the acceleration time. This acceleration time error will now be called dynamic error of acceleration time, and this will greatly affect the accuracy of the shearing length with the result that in order to improve the accuracy of the cutting length. It is required that the acceleration time of the motors can be controlled to the desired value and there exists a repetitive nature (reproductivity, that is, the same accuracy can be performed even though any times controlled repeatedly). For that purpose, as shown in FIG. 17, it is necessary to provide approximately 0.5 second at the acceleration time, approximately 0.3 second for the correction of the dynamic error of acceleration time thereafter, and further approximately 0.2 second as the affording

time, resulting approximately 1 second as total before the cutting action. However, in the conventional operating method, as shown in FIG. 16, the acceleration time is 0.5 second, and assuming that approximately 1 second of time is provided totally before the cutting action, it enters the range $p-q$ of cutting action during the correction of the acceleration time and the dynamic error of acceleration time with the result that the practical use of the cutting action becomes impossible. This invention overcomes the aforementioned disadvantages so as to improve it, and FIG. 18 shows its cutting cycle diagram, and FIG. 20 shows the acceleration time of shifting drive motors. This will now be described with reference to FIG. 18. Instead of point 0 in FIG. 15, point S is provided at the start and stop points, and the sections $s-y$ and $8-s$ are of the acceleration and deceleration range of shifting drive motors. The section $y-q$ is the uniform speed range of shifting drive motors, and the inner shear housing is synchronized with the feeding speed of the stock in the section $p-q$ of this section so as to give uniform speed so that it is conducted of cutting action and the leaving of the upper shear blade from the stock by the upper and lower shear blades.

* The change of the cutting length is conducted by changing the cutting cycle time t_c shown in FIG. 18.

Further, this will now be described in detail. In FIG. 12, the point S is the start point of the uniform speed range ($dx/d\phi = \text{constant}$ in range as $\phi = 225^\circ - 270^\circ - 315^\circ$) in the backward motion, and it is the most important point of this invention that this point is as its start point so that the range $s-y$ of the uniform speed range is taken in the acceleration range of shifting drive motors, which provides the following advantages:

1. The acceleration time can be lengthened so as to reduce the necessary motor power. As shown in FIG. 12, in the embodiment of this invention, $dx/d\phi$ of the section $s-y$ is $-8.33 (\text{mm}/^\circ)$ = constant, and the point s is start point ($d\phi/dt$)_{ats} = 0, and the point y is acceleration completing point, and accordingly in the embodiment of this invention, the rotating angle of the inner and outer eccentric during acceleration is 90° wherein (dx/dt)_{ats} = $180^\circ/\text{sec}$. (30 rpm) and in the section $s-y$.

Accordingly, if the shifting drive motor is linearly accelerated at a constant acceleration, the acceleration time becomes $t_{acc.} = 2 \times 90^\circ / 180^\circ/\text{sec.} = 1 \text{ sec.}$, and the acceleration is $180^\circ/\text{sec.}^2$. The speed of the inner housing in acceleration becomes $V_s = -180 \times 8.33 t = -1500 t$ (mm. sec.), to conduct linear acceleration proportional to the time. This is shown in FIGS. 19 and 20. FIG. 20 shows a rotating speed diagram of the shifting drive motors and the inner and outer eccentrics, and FIG. 19 is a speed diagram of the inner shear housing. That is, in FIGS. 19 and 20, the shifting drive motors and the inner and outer eccentrics are accelerated linearly in the section $s-y$ so that the accelerating time is 1.0 second, and becomes uniform rotating speed in the section $y-p-q$ so that it is linearly decelerated in the section $q-s$, and the decelerating time is 1.0 similar to the accelerating time.

On the one hand, correspondingly thereto, the inner shear housing is linearly accelerated in the section $s-y$ so that the deceleration-acceleration is conducted in the section $y-o-p$ for transferring from the backward motion to the forward motion so that the uniform speed synchronized with the stock is obtained in the section $p-q$, and the deceleration is conducted for deceleration

acceleration and stopping for transferring from the forward to backward motion in the section $g-r-s$. The comparison of FIG. 16 and FIGS. 19 and 20 is shown in FIG. 21, as understood therefrom, in the conventional operating method shown in FIG. 21(a), the acceleration time is only 0.5 second, but as shown in FIG. 21(b) in the embodiment of this invention,

1. the acceleration time is longer than 1.0 second,
2. the correction control time of the dynamic error of acceleration time of 0.5 second is provided before the cutting starting point p and the acceleration completing point y , and

15 3. the speed curve of the inner shear housing is linear proportional to the time in the acceleration section $s-y$ shown in FIG. 21(b) with the result that it shows that the acceleration torque of the shifting drive motors may be constant. As to the effects of the above paragraphs (1), (2) and (3) are as follows:

20 Paragraph (1) indicates the possibility of the half reduction of the necessary acceleration torque, half reduction of the motor power, and compactness of the shifting drive parts.

Paragraph (2) shows the possibility of the adoption of the feedback control system so called position control system using a computer having superior control accuracy instead of the conventional time control system.

25 Paragraph (3) shows the possibility of the accurate speed control of shifting drive motors having less dynamic error of acceleration time.

Thus, very preferable accuracy of cutting length of plus or minus 5 mm is obtained in the flying shear of the heavy load.

Operation of Upper Knife Holder Drive Motors

The flying shear shown in the embodiment of this invention conducts the contact of the upper and lower blades with the stock, cutting action of the upper and lower blades and leaving of the upper shear blade from the stock while the traveling speed of the inner shear housing in forward stroke is synchronized with the feeding speed of the stock in any of the continuous operations and start and stop operations of the shifting drive motors, and their aspects are shown in FIGS. 23 and 24. FIG. 23 shows the motion of the upper shear blade heretofore adopted, and FIG. 24 shows the motion of the upper shear blade of the embodiment of this invention.

45 The motion of the conventional upper shear blade will now be described with reference to FIG. 23.

50 The eccentric cam shaft for upper knife holder drive is driven with the same timing and rotating speed by the upper knife holder drive motors as shown in FIG. 23(a) as the rotation $s-y-p-q-s$ entirely correspondingly with the rotation $s-y-p-q-s$ (FIG. 23(d)) of the inner and outer eccentrics of shifting drive for inner shear housing. Accordingly, the motion of the upper shear blade draws on oval locus as shown by $s-y-p-q-s$ in FIG. 23(b).

55 In the embodiment of this invention, since the plate thickness maximum is 32 mm and the plate width maximum is 3550 mm, the shear blade length becomes approximately 3750 mm.

60 Assuming now that knife rake is 1/37.5, as shown in FIG. 22, it is necessary that the effective cutting stroke of $3750 \times 1/37.5 + 32 = 132 \text{ mm}$.

65 In the conventional operation shown in FIG. 23, since the effective stroke equal to 132 mm must be

practiced with the rotating angle $\gamma = 45^\circ$ of the upper knife holder drive eccentric cam shaft, the eccentricity of eccentric cam shaft for upper knife holder drive γ becomes as follows:

$$r = \text{effective stroke}/1 - \cos\gamma = 132/1 - 0.707 = 450 \text{ mm}$$

and it shows that the crank shaft having large crank radius is required, and the total stroke of the vertical direction of the upper knife holder becomes $2r = 900$ mm, and the upper knife holder and the front cross beam 32 and the back cross beam 33 for supporting in guide this becomes high depth so that overall the machine becomes large with the result that it has disadvantages such that the inertia mass of vertical direction and inertia mass of horizontal direction, so called flying mass, are increased.

The motion of the upper shear blade as the embodiment of this invention constructed for overcoming these disadvantages will now be described with reference to FIG. 24.

The upper knife holder drive eccentric cam shaft is driven by the upper knife holder drive motors by a timing different from that of the inner and outer eccentrics and at a rotating speed different from that of the inner and outer eccentrics as shown by $y-p-q-y$ in FIG. 24(a) with respect to the rotation $s-y-p-q-s$ of the inner and outer eccentrics of shifting drive for inner shear housing shown in FIG. 24(d). Therefore, the upper shear blade draws $yyy-p-q-yyy$ in FIG. 24(b) and crescent shape locus.

In the embodiment of this invention, as shown in FIG. 22, necessary effective stroke = 132 mm. Since the rotating speed of the eccentric cam shaft for driving the upper knife holder is twice the rotating speed of the inner and outer eccentrics of the shifting drive (30 rpm), that is 60 rpm, it is preferable that the effective stroke of 132 mm is performed at the rotating angle $\gamma = 90^\circ$ of the eccentric cam shaft for the upper knife holder drive, and the eccentricity of the eccentric cam shaft for the upper knife holder drive r becomes

$$r = \text{effective stroke}/1 - \cos\gamma = 132/1 = 132 \text{ mm}$$

Even if 8 mm is excessively provided, in comparison with the conventional one with $r = 140$ mm, it is understood that small eccentricity may be enough. The total stroke of the vertical direction of the upper knife holder becomes approximately 450 mm as shown in FIG. 24(b) in comparison with the conventional one becoming smaller in approximately one-half therewith, and the upper knife holder and the front and back cross beams 32 and 33 for supporting in guide in depth becomes small with the result that the machine becomes compact so as to reduce the flying mass.

FIG. 24(e) shows the relationship of the rotating speeds and the timings between the inner and outer eccentrics for shifting drive and eccentric cam shaft for the upper knife holder drive, and the motors for upper knife holder drive is also operated by the speed and timing corresponding to these.

Control of the Cutting Length

The duty of the flying shears is to cut the stock into lengths according to a given program or into lengths determined by a controlling computer for shearing without short ends. In addition, the cutting-off of the front end of a predetermined length is required.

In the embodiment of this invention from the formulation of this task as will be hereinafter described, more preferable position control is adopted so as to control

the shifting drive motors for the inner shear housing instead of the conventional system which are based on the control of the speed in accordance with a definite program. This position control always traces the position of the stock and the position of the shifting inner shear housing varying time by time in the course of the period between two consecutive cuts, and is the feedback control for controlling the speed of the shifting drive motors so that the position difference between both coincides with the desired cutting length. However, in the embodiment of this invention, instead of the position of the shifting inner shear housing, more preferable position control system may be obtained by using the position of the equivalent shear as will be hereinafter described.

In general, in the flying shear, the desired cutting length L_s is represented by the integral of the speed deviation V , between the feeding speed of the stock V_f and the traveling speed of the inner shear housing V_s , in the course of the period between two consecutive cuts, that is,

$$L_s = \int_0^{t_c} V dt = \int_0^{t_c} (V_f - V_s) dt \\ = \int_0^{t_c} V_f dt - \int_0^{t_c} V_s dt \quad (20)$$

wherein t_c stands for the period between the cuts. Accordingly, from the formula (20), the following formula (21) is obtained.

$$\Delta L = L_s - \int_0^t V dt = L_s - \int_0^t (V_f - V_s) dt \\ \Delta L = L_s - \left[\int_0^t V_f dt - \int_0^t V_s dt \right] \quad (21)$$

Then, using the formula (21), $V = V_f - V_s$ or V_f and V_s are separately caught, and integrated, and position control is conducted so that $\Delta L = 0$ is consistent in the cutting position ($t = t_c$) as a method as proposed. However, this is not proper for the position control due to the fact that as shown by the curve of the individual quantities of

$$\int_0^t V_f dt \text{ and } \int_0^t V_s dt,$$

in FIGS. 25(a) and 25(b), the difference of these two curves is

$$\int_0^t V dt, \quad \int_0^t V_s dt$$

becomes complicated curve over all region of the period between the cuts.

Then, in the embodiment of this invention, the following speed of the equivalent shear V_{seq} is adopted instead of the speed of the inner shear housing V_s . That is, as was described with reference to the formula (18), when the symbol L_z is used for the length which would be cut as ideal synchronism, so called basic cutting length,

$$L_z = 2\pi L/l (e_1 + e_2 - 2e_1 e_2/k)$$

Here, assuming that $L/l(e_1 + e_2 - 2e_1 e_2/k) = \text{constant} = R$

$$L_z = 2\pi R \quad (22)$$

the following formula is existent, and the movement of

the reciprocating flying shear as the embodiment of this invention is as shown in FIG. 26.

$2\pi R = L_z$ (the basic cutting length) as circumference of track of cutters provided for an equivalent shear as substituted in movement to be considered. Therefore, assuming that the equivalent circumferential speed of the equivalent shear, called hereinafter merely the speed of the equivalent shear, is V_{seq} ,

$$V_{seq} = R(d\theta/dt) = L_z/2\pi \cdot d\theta/dt \quad (23)$$

Accordingly, the integral of the speed deviation V_{eq} between the feeding speed of the stock V_f and the speed of the equivalent shear V_{seq} becomes as follows:

$$\int_0^{t_c} V_{eq} dt = \int_0^{t_c} (V_f - V_{seq}) dt = \int_0^{t_c} V_f dt - \int_0^{t_c} V_{seq} dt = L_s - L_z \quad (24)$$

because

$$\int_0^{t_c} V_f dt = L_s: \text{Desired cutting length.}$$

And, from the formula (23),

$$\int_0^{t_c} V_{seq} dt = \int_0^{t_c} R \left(\frac{d\theta}{dt} \right) dt = R \int_0^{2\pi} d\theta = 2\pi R = L_z: \text{Basic cutting length.}$$

Thus, the formula (24) shows that the integral of the speed deviation "V_{eq}" between the speeds of the stock and of the equivalent shear, during the period between two consecutive cuts "t_c" is equal to the increment in length of the piece cut "(L_s-L_z)" which must be achieved by changing the speed of the equivalent shear.

From the formula (24), the following formula is obtained.

$$\Delta L_{eq} = (L_s - L_z) - \int_0^{t_c} V_{eq} dt = (L_s - L_z) - \int_0^{t_c} (V_f - V_{seq}) dt$$

5

10

45

or

$$= (L_s - L_z) - \left[\int_0^{t_c} V_f dt - \int_0^{t_c} V_{seq} dt \right] \quad (25)$$

Wherein t represents a lapsed time from the zero position as a standard point at the position of completion of the preceding cut, that is, $t = 0$, and the integrated values until now are instantaneously cancelled at the position of completion of the succeeding cut, and again the zero position is taken with $t = 0$ together.

Then, in the embodiment of this invention, using the formula (25), and $V_{eq} = V_f - V_{seq}$ or V_f and V_{seq} are separately caught, and integrated, and a method of conducting the position control so that $\Delta L_{eq} = 0$ is consistent at the cutting position ($t = t_c$) is adopted.

As shown by the curves of the individual quantities of

$$\int_0^t V_f dt \text{ and } \int_0^t V_{seq} dt$$

in FIGS. 27(a) and 27(b), the difference of these two curves becomes

$$\int_0^t V_{eq} dt, \quad \int_0^t V_{eq} dt$$

becomes the combination of the straight line and square curve over all the region of the period between the cuts so that the adoption of the position control is easy.

Now, the basic formulae required for the position control of the embodiment of this invention is arranged to be shown by the following Tables 1 and 2 wherein Table 1 shows the case of the continuous operation of the shifting drive motors and Table 2 shows the start and stop operation of the shifting drive motors. Table 1 is the basic formulae for position control in the case of continuous operation as a table, and Table 2 shows the basic formulae for position control in the case of start and stop operation as a table adopted in the embodiment of this invention.

(formula 43)

$$\bar{V}_{seq} \cdot sol = \bar{V}_f \mp \sqrt{2\alpha \left[\left(L_s - \sum_0^t P_f dt \right) - \left(L_z - \sum_0^t P_s dt \right) \right]} \quad (-) \text{ for } L_s > L_z \quad (+) \text{ for } L_s < L_z$$

(formula 44)

$$\bar{V}_{seq} \cdot sol = \bar{V}_f \text{ (Synchronizing for cutting)}$$

TABLE 2.—BASIC FORMULAS FOR POSITION CONTROL IN THE CASE OF START-STOP OPERATION

Range	Movements of the equivalent shear			Movements of the stock	Quantities of
	$\int_0^t V_{seq} dt$	$\int_0^t V_f dt$	$\int_0^t V_{seq} dt$		
	$= \sum_0^t P_s$	$= \sum_0^t P_f$			
Z	0	0	0	$\bar{V}_{seq} \cdot sol$ (Synchronizing for knife leaving)	
— q —	$1q = \frac{1}{8} L_z$	$\frac{1}{8} L_z$	0		
S	$1s = \frac{3}{8} L_z$	$\frac{5}{8} L_z$	$\frac{1}{4} L_z$		
— S —	$1s = \frac{3}{8} L_z$	$L_s - \frac{7}{8} L_z$	$L_s - \frac{5}{4} L_z$	$\bar{V}_{seq} \cdot sol = 0$ (Stopping)	
— y —	$1y - \frac{5}{8} L_z$	$L_s - \frac{3}{8} L_z$	$L_s - L_z$		
Z	$1z = L_z$	L_s	$L_s - L_z$	$\bar{V}_{seq} \cdot sol = \bar{V}_f$ (Synchronizing for cutting)	

The development of the basic formulae of the case of the continuous operation shown in Table 1 will now be described.

The formula (24) is represented as follows:

$$L_s - L_z = \int_0^{t_s} V_{seq} dt = \int_{t_z=0}^{t_s} V_{seq} dt + \int_{t_s}^{t_s} V_{seq} dt + \int_{t_s}^{t_y} V_{seq} dt + \int_{t_y}^{t_z} V_{seq} dt \quad (26)$$

In the range: z-q,

$V_{eq} = 0$: Condition in synchronism for knife leaving.

$$\int_0^t V_{seq} dt = 0 \quad (27)$$

$$\int_0^{t_s} V_{seq} dt = \int_0^{t_s} V_f dt - \int_0^{t_s} V_{seq} dt = 1q - 1q = 0 \quad (28)$$

In the range: q-s,

$V_{eq} = \alpha t$: Condition for changing of the speed deviation.

$$at t = t_s \quad V_{eq} = 0$$

$$at t = t_s \quad V_{eq} = B$$

$$t = V_{eq}/\alpha, t_s - t_q = B/\alpha$$

wherein

α : (mm/sec²) uniform acceleration or deceleration of the speed deviation V_{eq} ,

B: (mm/sec) reached speed deviation at position s.

$$\int_{t_q}^t V_{seq} dt = \frac{1}{2} \alpha t^2 = \frac{V^2 eq}{2\alpha} \quad (29)$$

$$\int_{t_q}^{t_s} V_{seq} dt = \frac{B^2}{2\alpha} \quad (30)$$

On the other hand, if V_f = uniform speed,

$$\begin{aligned} \int_{t_q}^{t_s} V_{seq} dt &= \int_{t_q}^{t_s} V_f dt - \int_{t_q}^{t_s} V_{seq} dt \\ &= V_f \frac{B}{\alpha} - (1s - 1q) \end{aligned} \quad (31)$$

In the range: s-y,

$V_{eq} = B - \alpha t$: Condition for changing of the speed deviation.

$$at t = t_s \quad V_{eq} = B$$

$$at t = t_y \quad V_{eq} = 0$$

$$t = B - V_{eq}/\alpha, t_y - t_s = B/60$$

$$\int_{t_s}^t V_{seq} dt = Bt - \frac{1}{2} \alpha t^2 = \frac{B^2 - V_{eq}^2}{2} \quad (32)$$

$$\int_{t_s}^{t_y} V_{seq} dt = \frac{B^2}{2\alpha} \quad (33)$$

On the other hand, if V_f = uniform speed,

$$\begin{aligned} \int_{t_s}^{t_y} V_{seq} dt &= \int_{t_s}^{t_y} V_f dt - \int_{t_s}^{t_y} V_{seq} dt \\ &= V_f \frac{B}{\alpha} - (1y - 1s) \end{aligned} \quad (34)$$

In the range: y-z,

$V_{eq} = 0$: Condition in synchronism for cutting

$$\int_{t_y}^t V_{seq} dt = 0 \quad (35)$$

$$\begin{aligned} \int_{t_y}^{t_z} V_{seq} dt &= \int_{t_y}^{t_z} V_f dt - \int_{t_y}^{t_z} V_{seq} dt \\ &= (1z - 1y) - (1z - 1y) = 0 \end{aligned} \quad (36)$$

If the conditions of the above respective sections are substituted to the formula (26), that is, the formulae (28), (30), (33) and (36) are substituted to the formula (26),

$$Ls - Lz = B^2/\alpha \quad (37)$$

And, if the formulae (28), (31), (34) and (36) are substituted to the formula (26),

$$Ls - Lz = 2VfB/\alpha - (1y - 1q) \quad (38)$$

is obtained.

From the formulae (37) and (38),

$$B = \alpha/2Vf [(Ls - Lz) + (1y - 1q)] \quad (39)$$

$$\alpha = 4V^2f Ls - Lz/[(Ls - Lz) + (1y - 1q)]2 \quad (40)$$

are obtained. And, in the embodiment of this invention, as shown in FIG. 26, since the following formula is consistent,

$$1y - 1q = 5/8 Lz - 1/8 Lz = 1/2 Lz$$

if this is substituted to the formulae (39) and (40),

$$B = \alpha/2Vf (Ls - Lz/2) \quad (41)$$

15

Sum of the impulses Pf and proportional to the movement of the stock,

$$\sum_0^t Pf:$$

Sum of the impulses Ps and proportional to the movement of the equivalent shear.

In the range: $s-y$, from the formulae (27), (30) and (32)

$$\int_0^t Veqdt = \int_0^{tq} Veqdt + \int_{tq}^{ts} Veqdt + \int_{ts}^t Veqdt$$

$$= \frac{B^2}{2\alpha} + \frac{B^2 - Veq^2}{2\alpha} = \frac{B^2}{\alpha} - \frac{Veq^2}{2\alpha} \quad (44)$$

On the one hand, if the formula (37) is substituted to the above formula,

$$\int_0^t Veqdt = (Ls - Lz) - \frac{Veq^2}{2\alpha}$$

$$Veq = \pm \sqrt{2\alpha \left[(Ls - Lz) - \int_0^t Veqdt \right]}$$

$$Vseq \cdot sol = Vf \mp \sqrt{2\alpha \left[(Ls - \int_0^t Vfdt) - (Lz - \int_0^t Vseq \cdot istdt) \right]}$$

$$= Vf \mp \sqrt{2\alpha \left[(Ls - \sum_0^t Pf) - (Lz - \sum_0^t Ps) \right]}$$

are obtained. As to the symbols ($\mp$), if $Ls > Lz$, it is ($-$), while if $Ls < Lz$, it is ($+$).

In the range: $y-z$, from the formula (35), the following formula is obtained:

$Vseq \cdot sol = Vf$. Then, the basic formula of the case of the start and stop operation shown in Table 2 will now be described.

The formula (24) is represented as follows:

$$Ls - Lz = \int_0^{tc} Veqdt = \int_{tz=0}^{tq} Veqdt + \int_{tq}^{ts} Veqdt$$

$$+ \int_{ts}^{ts'} Veqdt + \int_{ts'}^{ty} Veqdt + \int_{ty}^{tz=tc} Veqdt \quad (45)$$

In the range: $z-q$,

$Veq = 0$: Condition in synchronism for knife leaving is applied with the formulae (27) and (28) as they are.

In the range: $q-s$

$Veq = \alpha t$: Condition for deceleration of the equivalent shear.

$$at t = tq \quad Veq = 0$$

$$at t = ts \quad Veq = Vf$$

$$t = Veq/\alpha, ts - tq = Vf/\alpha$$

As to the symbols ($\mp$), if $Ls > Lz$, ($-$), while if $Ls < Lz$, ($+$) is used, wherein

$$\int_0^t Vseq \cdot istdt:$$

Measured movement of the equivalent shear,

$$\sum_0^t Pf:$$

Sum of the impulses Pf , and proportional to the movement of the stock,

$$\sum_0^t Ps:$$

Sum of the impulses Ps and proportional to the movement of the equivalent shear.

In the range: $s-y$, from the formulae (27), (30) and (32)

are consistent, and they are applied by using the formula (29) as it is, and by replacing the formulae (30) and (31) with $B = Vf$. In the range: $s-s$

$V_{eq} = Vf$: Condition for stopping.

$$\int_{ts}^{ts'} V_{eq} dt = \int_{ts}^{ts'} Vf dt \quad (46)$$

In the range: $s-y$

$V_{eq} = Vf - \alpha t$: Condition for acceleration of the equivalent shear.

$$at t = ts' \quad V_{eq} = Vf$$

$$at t = ty \quad V_{eq} = 0$$

$$t = Vf - V_{eq}/\alpha, ty - ts' = Vf/\alpha$$

are consistent and the aforementioned formulae (32), (33) and (34) are applied by replacing with $B = Vf$. In the range: $y-z$

$V_{eq} = 0$: Condition in synchronism for cutting are applied with the aforementioned formulae (35) and (36) as they are.

If the conditions of the respective sections are substituted in the formula (45), that is, the formulae (28), (30), (46), (33) and (36) are substituted to the formula (45), however, $B = Vf$ is replaced,

$$Ls - Lz = \frac{Vf^2}{\alpha} + \int_{ts}^{ts'} Vf dt \quad (47)$$

If the formulae (28), (31), (46), (34) and (36) are substituted to the formula (45), however, $B = Vf$ is replaced,

$$Ls - Lz = \frac{2Vf^2}{\alpha} - (ly - 1q) + \int_{ts}^{ts'} Vf dt \quad (48)$$

is obtained.

From the formulae (47) and (48)

$$\alpha = Vf^2/(ly - 1q) \quad (49)$$

In the embodiment of this invention, as shown in FIG. 26, since the following formula is consistent, if this is substituted to the formula (49),

$$(ly - 1q) = 1/2 Lz$$

$$\alpha = 2Vf^2/Lz \quad (50)$$

is obtained.

If the formula (50) is substituted to the formula (47), the following formula is obtained,

$$\int_{ts}^{ts'} Vf dt = Ls - \frac{3}{2} Lz \quad (51)$$

Therefore, α may be given from the formula (50) as the feeding speed of the stock as the function, and the movement of the stock

$$\int_{ts}^{ts'} Vf dt$$

is given as the function of the desired cutting length Ls in the stopping period of the equivalent shear at the position S by the formula (51). Then, the desired speed of the equivalent shear $V_{seq} \cdot sol$ at the respective sections is expressed as the following formulae:

In the range: $z-q$

$$V_{seq} \cdot sol = Vf$$

In the range: $q-s$

$$V_{seq} \cdot sol = Vf - \sqrt{2\alpha \left[\sum_0^t Pf - \sum_0^t Ps \right]} \quad (52)$$

In the range: $s-s$

$$V_{seq} \cdot sol = 0 \quad (\text{stopping})$$

In the range: $s-y$

$$V_{seq} \cdot sol = Vf - \sqrt{2\alpha \left[(Ls - \sum_0^t Pf) - (Lz - \sum_0^t Ps) \right]} \quad (53)$$

10 In the range: $y-z$

$$V_{seq} \cdot sol = Vf.$$

Thus, in the embodiment of this invention, the cutting length of the range of $1/2 Lz < Ls \leq 3/2 Lz$ are obtained theoretically by giving speed variation to the speed of the equivalent in the range $q-y$ in case of the continuous operation, and in case of the start and stop operation, the cutting length may be obtained in the range of $Ls > 3/2 Lz$.

15 Then, six types of the patterns of the speed changing of the equivalent shear introduced by using the basic formulae shown in Tables 1 and 2 are shown in Table 3.

In the Table 3, the pattern (1) is to obtain the shorter cutting length Ls than the basic length Lz .

20 In the embodiment of this invention, $Lz = 3000$ mm. Now, if $Ls = 2500$ mm, $Vf = 750$ mm/sec. are consistent, from Table 1 and the formula (42), $\alpha = 4 \times 750^2 \times 2500 - 3000/(2500 - 1500)^2 = -1125$

25 $mm/sec.^2$ are obtained.

In the embodiment of this invention, $|\alpha| \leq 1500$ mm/sec.² is limited, but this condition is satisfied.

From the formula (41)

$$35 B = -1125/2 \times 750 (2500 - 1500) = -750 \text{ mm/sec.}$$

$$B = Vf - V_{seq} \cdot at s$$

$$V_{seq} \cdot at s = 750 + 750 = 1500 \text{ mm/sec.}$$

are obtained.

In the embodiment of this invention, it is limited to

40 $V_{seq} \text{ max} \leq 1500$ mm/sec. This condition is also satisfied. Therefore, the pattern (1) accelerates the equivalent shear of the range $q-s$, and decelerates in the range $s-y$, and moves faster speed than that of the stock of the equivalent shear in the range $q-s-y$. Pattern (2) contemplates to obtain the cutting length Ls equal to the basic cutting length. That is, $Ls = Lz = 3000$ mm, and from Table 1 and formula (42) $\alpha = 0$ is consistent regardless of the feeding speed of the stock Vf , and the equivalent shear always synchronized with the stock at $V_{seq} \cdot sol$

45 $- Vf$ over all region of the range $z-q-s-y-z$ so as to move it.

Pattern (3) contemplates to obtain the shorter cutting length Ls than $3/2 Lz$ and longer than the basic length Lz . Now, assuming that $Ls = 3750$ mm, $Vf = 1500$ mm/sec., from Table 1 and the formula (42), $\alpha = 4 \times 1500^2 \times 3750 - 3000/(3750 - 1500)^2 = 1333$ mm/sec.²

55 is obtained. And, from the formula (41), the following formula is obtained.

$$60 B = 1333/2 \times 1500 (3750 - 1500) = 1000 \text{ mm/sec.}$$

$$V_{seq} \cdot at s = 1500 - 1000 = 500 \text{ mm/sec.}$$

Therefore, the pattern (3) decelerates the equivalent shear in the range of $q-s$ and accelerates in the range $s-y$, and shows that in the range $q-s-y$ the equivalent shear moves slower than the speed of the stock.

65 Pattern (4) contemplates to obtain $Ls = 3/2 Ls = 4500$ mm, and now, if $Vf = 1500$ mm/sec., from Table 1 and formula (42),

TABLE 3

PATTERNS OF SPEED CHANGING		RELATION BETWEEN $\bar{V}_f$ AND $\bar{V}_{seq}$	RELATION BETWEEN $\sum_t P_f$ AND $\sum_t P_s$
1	INCREASING SPEED AT RANGE $0 - t_c$		
2	UNIFORM SPEED		
3	CONTINUOUS OPERATION AT RANGE $0 - t_c$		
4	DECREASING SPEED AT RANGE $0 - t_c$		
5	PIECE CUT		
6	CUTTING OFF THE FRONT ENDS		

$$\alpha = 4 \times 1500^2 \times 4500 - 3000 / (4500 - 1500)^2 = 1500 \text{ mm/sec.}^2$$

And, from the formula (41),

$$B = 1500/2 \times 1500 (4500 - 1500) = 1500 \text{ mm/sec.}^2$$

$$V_{eq} \text{ at } s = 1500 - 1500 = 0$$

are obtained.

That is, it is entirely the same as those of pattern (3) except that it becomes instantaneously $V_{eq} = 0$ at the

position S in type, and it is said that it is the same as the case of

$$\int_{ts}^{ts'} V_{eq} dt = 0$$

of pattern (5) as well be hereinafter described.

Pattern (5) contemplates to obtain the cutting length over $L_s < 3/2 L_z = 4500$ mm, and now assuming that $V_f = 1500$ mm/sec., and $L_s = 5250$ mm, from Table 2 and the formula (50),

$$\alpha = 2 \times 1500^2 / 3000 = 1500 \text{ mm/sec.}^2$$

from the formula (51)

$$\int_{ts}^{ts'} V_{eq} dt = \int_{ts}^{ts'} V_f dt = 5250 - 4500 = 750 \text{ mm}$$

are obtained.

Therefore, the pattern (5) shows the deceleration-stop of the equivalent shear in the range $q-s$, stop during the movement of 750 mm of the stock in the position S and starting -acceleration in the range $s-y$.

As was described heretofore, with reference to Table 3, in the embodiment of this invention, since the limiting conditions of $750 \leq V_f \leq 1500$ mm/sec., $0 \leq V_{seq} = 1500$ mm/sec., $|\alpha| \leq 1500$ mm/sec.², $L_z = 3000$ mm, are provided, the possible cutting range is in the range of 2500–3000–4500 mm in case of the continuous operation of the shifting drive motors, and is in the range of over 4500 mm any length in case of the start and stop operation, with the result it may obtain any desired cutting length over 2500 mm, and pattern (6) is the first case of the cutting-ff of the front end of the stock, and means the first cut. Before the first cut starts, the equivalent shear stops at the position S, and it must be started at the timing corresponding to the first cutting length with the result that the basic formula in the range $s-y$ of the case of the start and stop operation, that is, the start-acceleration command by the formula (53) shown in Table 2 are used as they are preferably.

According, in order to apply the equivalent shear as desired speed in case of the first cut by the formula (53), the method adopted in the embodiment of this invention will now be described referring to FIG. 28.

The initial conditions of the case of the first cutting will now be described, for the preparation of the first cutting, the set values for control is all once cancelled. The equivalent shear is stopped correctly at the position S. The stock is disposed far from the position i for starting to control the first cutting at a distance of L_i (mm) from the cutting line of the bottom knife at the zero-position for completing to cut of the equivalent shear. The control for the first cutting is started at the moment when the front edge of the stock reaches the position i under the aforementioned initial conditions, but assuming that the desired first cutting length of the

$$\begin{aligned} V_{seq} \cdot sol &= V_f - \sqrt{2\alpha \left[\left(L_{so} + L_i + \frac{5}{8} L_z \right) - \left(\frac{5}{8} L_z + \sum_{ts}^t Pf \right) \right] - \left[\left(\frac{3}{8} L_z + \frac{5}{8} L_z \right) - \left(\frac{3}{8} L_z + \sum_{ts'}^t Ps \right) \right]} \\ &= V_f - \sqrt{2\alpha \left[\left(L_s - \sum_o^t Pf \right) - \left(L_z - \sum_o^t Ps \right) \right]} \end{aligned}$$

first cutting is expressed by L_{so} , as shown in FIG. 28, the stock must advance in the amount from the time point ts for starting to control for the first cutting to the time point tc for completing the first cutting as follows:

$$\sum_{ts}^{tc} Pf = L_{so} + L_i \quad (54)$$

At the time point ts for starting to control for the first cutting, if the equivalent shear is stopped at the position S in consideration, the stock is regarded as advanced in the amount of

$$\sum_0^{ts} Pf = \frac{5}{8} L_z,$$

it becomes:

$$\sum_0^{ts} Pf = \sum_0^{ts} Pf + \sum_{ts}^{t} Pf = \frac{5}{8} L_z + \sum_{ts}^t Pf \quad (55)$$

From the formulae (54) and (55), the following formula is obtained:

$$L_s = \sum_0^{tc} Pf = \sum_0^{ts} Pf + \sum_{ts}^{tc} Pf = L_{so} + L_i + \frac{5}{8} L_z \quad (56)$$

wherein L_s is regarded as an imaginary desired first cutting length, the actual length of the case of the first cutting is always L_{so} . On the other hand, the equivalent shear must advance from the start point ts' for the first cutting to the point tc for completing the first cutting in the amount:

$$\sum_{ts'}^{tc} Ps = L_z - L_i = \frac{5}{8} L_z \quad (57)$$

Since the equivalent shear must be stopped at the position S during the period from the point ts for starting to control for the first cutting to the point ts' for starting the equivalent shear of the first cutting, the equivalent shear is regarded as advancing in the amount:

$$\sum_0^{ts} Ps = \sum_0^{ts'} Ps = L_i = \frac{3}{8} L_z$$

always in advance with the result that

$$\sum_0^{ts} Ps = \sum_0^{ts'} Ps + \sum_{ts'}^{t} Ps = \frac{3}{8} L_z + \sum_{ts'}^t Ps \quad (58)$$

without saying that from the formulae (57) and (58), the following formula is obtained:

$$\sum_0^{tc} Ps = \sum_0^{ts} Ps + \sum_{ts}^{t} Ps = \frac{3}{8} L_z + \frac{5}{8} L_z = L_z \quad (59)$$

wherein L_z is regarded as an imaginary basic cutting length, and the actual equivalent shear in movement of the case of the first cutting is always

$$L_z = L_i = \frac{5}{8} L_z$$

As the foregoing description, by introducing the concept of the imaginary desired first cutting length L_s and the imaginary basic cutting length L_z , the start-acceleration command in the section $s-y$ from the formulae (56) and (59) becomes the following formula:

which is entirely the same as the basic formula (53) in the section $s-y$ of the case of the start and stop operation shown in Table 2, wherein the following conditions are consistent,

$$\alpha = 2Vf^2/Lz$$

$$\int_{ts}^{ts'} Veqdt = \int_{ts}^{ts'} Vfdt = \left(Lso + Li + \frac{5}{8} Lz \right) - \frac{3}{2} Lz = Ls - \frac{3}{2} Lz$$

Thus, it was described that in the first cutting the basic formula of the case of the start and stop operation could be used, but in order to determine the position i for starting to control for the first cutting, the following limiting condition must be satisfied. That is, the limiting conditions of the case of the start and stop operation shown in Table 2.

$$Ls = Lso + Li + 5/8 Lz > 3/2 Lz \quad (60)$$

From the formula (60), it becomes as follows:

$$Li > 7/8 Lz - Lso \quad (61)$$

Since the minimum of Lso in the formula (61) is zero, if assuming that

$$Li > 7/8 Lz \quad (62)$$

the limiting condition for obtaining the first cutting length of $0 < Lso < \infty$ is theoretically satisfied. In the embodiment of this invention, since $Lz = 3000$ mm, it may only be $Li > 2625$ mm, and accordingly, the photoelectric relay 209 for detecting the front edge of the stock at the first cut at the position of

$$Li = 3000 \text{ mm} > 2625 \text{ mm}$$

as shown in FIG. 28.

As one example, the case of the first cut desired length $Lso = 500$ mm and $Vf = 1500$ mm/sec. will now be described. Since $Lz = 3000$ mm and $Li = 3000$ mm, the imaginary desired first cutting length Ls is from the formula (56)

$$Ls = 500 + 3000 + 1875 = 5375 \text{ mm.}$$

The acceleration is from the formula (50)

$$\alpha = 2 \times 1500^2/3000 = 1500 \text{ mm/sec.}^2$$

The distance that the stock advances from the point for starting to control for the first cutting to the point that the start command of the equivalent shear is given as follows from the formula (51)

$$\int_{ts}^{ts'} Veqdt = \int_{ts}^{ts'} Vfdt = 5375 - 4500 = 875 \text{ mm}$$

Accordingly, if the front end of the stock reaches the position i of $Li = 3000$, the control for the first cutting is started at the moment at the same time the adding-up of the movement of the stock is started. In this case, the desired speed of the equivalent shear, $Vseq$ sol = 0, and the equivalent shear is stopped. If the stock is advanced from the start of the adding-up, the equivalent shear is started so that it is accelerated by the desired speed calculated by the formulae (50) and (53) in the section $s-y$. Hereinafter, in the section $y-z$, $Vseq$ sol = Vf , and cutting is conducted in the section $p-z$ so that at the position z it becomes the shearing completing point, and then the subsequent piece cut is at once prepared. In order to conduct the speed changing operation of six patterns as was described, in the embodiment of this invention the position control system of the concept as shown in FIG. 29 is adopted. As to FIG. 29, it will be described.

A tacho-generator 301 and an impulse-generator 302 are fitted to the shaft end of a measuring roll 208. The tacho-generator 301 gives the quantity of the speed corresponding to the feeding speed Vf of the stock. The impulse-generator 302 gives the impulses Pf corresponding to the movement of the stock, so that this adding-up

$$\sum_0^t Pf$$

gives the quantity of the movement of the stock. At the shaft end of the shifting drive inner eccentrics drive shaft 60 are fitted a tacho-generator 303, an impulse generator 304, and position indicator 305 of the equivalent shear. The tacho-generator 303 provides the quantity of the speed corresponding to the present speed $Vseq$ is of the equivalent shear.

The impulse generator 304 provides the impulses Ps corresponding to the movement of the equivalent shear so that the adding-up value thereof

$$\sum_0^t Ps$$

provides the quantity of movement of the equivalent shear. The position indicator 305 provides mainly the impulses for indicating the position z for completing the shearing and is used for setting the zero point for the piece cut, or is used for indicating the position $q-s-y-p$ in response to the requirement. A photoelectric relay 209 for detecting the front end of the stock is provided at the position i of the distance Li from the cutting line of the bottom knife at the position z for completing the cutting of the equivalent shear. This provides the impulse for indicating the moment detected by the photoelectric relay 209 at the front end of the stock and is used for setting the zero point for the first cut. The introduction 306 and 307 provides constants Li and Lz , respectively. The introduction 310 provides the desired cutting length. However, only in case of the first cut, the following formula (56) is provided.

$$Ls = Lso + Li + 5/8 Lz \quad (56)$$

Adders 309 and 308 add the impulses Pf and Ps . However, only in case of the first cut, it adds the following formulae (55) and (58)

$$\sum_0^t Pf = \frac{5}{8} Lz + \sum_{ts}^t Pf \quad (55)$$

$$\sum_0^t Ps = \frac{3}{8} Lz + \sum_{ts'}^t Ps \quad (58)$$

and the signal of the time ts is provided by the impulse of the photoelectric relay 209. Therefore, this movement is called zero setting for the first cut as aforesaid. In case of the piece cut, the adders 309 and 310

$$\sum_0^t Pf = \sum_{tz}^t Pf \quad \text{and} \quad \sum_0^t Ps = \sum_{tz}^t Ps,$$

respectively, and the signal of the time tz is provided by the impulse for indicating the position z for completing the cutting from the position indicator 305.

Therefore, this moment is called zero setting for piece cut as previously described. The zero setting for the first cut incorporates the introduction of the desired first cutting length Lso , and the zero setting for the piece cut incorporates the introduction of the desired cutting length $Ls1, Ls2, \dots$ subsequently thereto. Moreover, the blocks 311 and 312 for calculating ac-

cording to the basic formulae for position control — formulae (42) and (50), (43) and (52), (44) and (53) shown in Tables 1 and 2 — is proposed with computer as one example. The speed command $V_{seq\ sol}$ to be existent of the equivalent shear and the present speed $V_{seq\ ist}$ thus obtained are compared by comparator 313, and these differences fed to automatic speed regulator 314 so that the feedback speed control of the shifting drive motors 76, 76' and 77, 77' is conducted by the control unit of motors 315. On the one hand, the impulse for indicating the position- y of the position indicator 305 commands the starting of the upper knife holder drive motors 22 and 22'. The impulse for indicating the position- q of the position indicator 305 commands the starting of the deceleration of the upper knife holder drive motors 22 and 22'. In this case, the speed of the upper knife holder drive motors may be varied proportional to the square of the feeding speed V_f of the stock for holding the relationship shown in FIG. 24 (e), but the detail description will be omitted. A tacho-generator 316, impulse-generator 317 and position indicator 318 are mounted to the shaft end of the upper knife holder drive eccentric cam shaft 24 upon requirement. The position- y of the position indicator indicates the stop position of the eccentric cam shaft, the position- p indicates the position for completing the deceleration, the position- z indicates the position for completing the cutting, and the position- q indicates the position for starting the deceleration. The feeding pinch rolls 207 are used for moving the stock as accurate uniform speed as possible.

As the foregoing description, the following advantages are provided in accordance with the present invention:

1. Since the upper knife holder drive 20 is mounted on the stationary outer housing 10 and the eccentric cam shaft 24 rotating as the output shaft of the upper knife holder drive 20 and the upper knife holder 26 are connected by the connecting rods 25 and 25', the upper knife holder drive is not necessary to run but the mechanical parts of the portion relative to the reciprocating traveling motion may be limited to minimum so that the structure may be simplified and the inertia may also be greatly reduced and the shifting drive 50 and the electric motor capacity may be small enough.

2. Since the reciprocating inside shiftable shear housing 30 is supported by the shifting supports 40 instead of the conventional sliding surface, the conventional problems such as wear and unbalanced contact of the sliding surface, engagement of scale, seizure are completely eliminated and the proper lubrication and sealing for scale around the couplings of the link mechanism are easy, its operation becomes stable and the life of the parts is enhanced and the frictional resistance is also less with the result that the power consumption may be less. And, since this link mechanism 40 moves substantially linearly, if several sets of the same size of the links are installed as shown in the embodiment of this invention, the shiftable inner shear housing 30 moves longitudinally in horizontal manner in parallel motion with the result that the inertia of the elevational direction is not produced during running of the shiftable inner shear housing 30, the elevational load applied to the base is reduced and the angle forming with the cutting stock and the elevational cutting edge does not vary so as to lengthen the life of the edge with preferable cutting surface.

3. Since the shifting drive 50 has mainly circular gear and circular eccentric cam of the components without using any of non-circular gear and non-circular eccentric cam which is difficult to accurately manufacture, its production is easy and it is possible to design for enduring high speed and heavy load. Further, desired constant speed section and travelling speed may be obtained by varying the eccentricity of the inner and outer eccentric cams and the lever ratio, and since the accuracy of the constant speed is also high as shown in FIG. 13, the sliding distance on the stock of the cutting edge is small due to the error on the synchronizing speed between the stock during cutting and the upper and lower cutting edges, and the shock applied to the edge is reduced, and preferable cut surface and long life of the edge may be obtained.

4. Since the drive motors are intermittently operated at the start point of the constant speed section of the backward stroke of the shiftable inner shear housing 30 as the start point for starting the shifting drive 50, the accelerating time may be lengthened, the acceleration thereof is reduced, the shifting drive is made compact, and the motor capacity may be reduced. In addition, since the acceleration of the drive motors is completed within the constant speed section of the backward stroke of the shiftable inner shear housing 30, the speed of the shiftable inner shear housing 30 during acceleration is proportional to the speed of the motor, with the result that the fluctuation of the shifting torque during acceleration is less, and the accelerating time of the motor is more accurately controlled. And, the time for correcting the dynamic error during acceleration with sufficient time before the start of the cutting is provided even after the completion of acceleration of the motor, the feedback position control system may be adopted for controlling the motor speed, so that preferable cutting length in accuracy may be obtained.

5. Since the upper knife holder drive 20 is driven by another motor from the shifting drive motor, it is also possible upon requirement that the stock may be stopped similar to the conventional stationary arranged shear while the shifting drive motor is stopped so as to cut. Further, since the rotating speed of the eccentric cam shaft of the upper knife holder drive is rotated faster than the rotating speed of the inner and outer eccentric cam for driving the shiftable inner housing, the eccentric amount of the eccentric cam shaft for driving the upper knife holder is lessened and the elevational moving amount of the upper knife holder is restricted on minimum required limit with the result that the machine is made compact and the flying mass may be reduced.

6. Since the feedback position control is all conducted by the operation control of 6 patterns as shown in the Table 3, even if the desired cutting length is varied, the operation is not once stopped but it is possible to continuously conduct for piece cuts and to obtain the cutting length of high accuracy so as to obtain the subsequent various desired lengths.

Thus, this invention is applied to the shiftable shear required for high cutting force, high cutting speed, high cutting length accuracy, preferable cutting surface, piece cuts length different in every cutting as in the example of the shear for cutting broad heavy plates installed on the cutting line in the finishing equipment of the roll mill plane so as to provide advantageous effects.

What is claimed is:

1. In a flying shear adapted to be installed in the shearing line at the finished end of the heavy plate rolling mill plant for shearing metal plates in various lengths, having a stationary outer housing mounted on bed plates, a pair of upper knife holder drives mounted on said outer housing and driving an eccentric cam shaft journaled on said outer housing for lifting and lowering an upper knife holder, a shiftable inner shear housing moving parallel to the traveling stock, said inner housing being inside of said outer housing, guiding said liftable upper knife holder and carrying a lower knife holder to effect a shearing action between said upper knife holder, a pair of shifting supports bearing on said outer housing for supporting said inner shear housing, and a pair of shifting drives mounted on said bed plates for reciprocating said inner shear housing in synchronism with the traveling stock at the time of cutting; the improvement wherein an inner eccentric cam is fixed to a drive shaft for one-way rotation, an outer eccentric cam is movably engaged with the outer periphery of said inner eccentric cam and is so mounted as to inversely drive with the same speed as the inner eccentric cam at the same time the connecting rod movably engaged with the outer periphery of said outer eccentric cam, is connected directly or through a rockable lever to the flying shear housing, whereby the composite motion of the inner and outer eccentric cams are converted to the reciprocating motion of the knife holder.

30

2. In a flying shear installed in the shearing line at the finished end of the heavy plate rolling mill plant for shearing metal plates in various lengths, having a stationary outer housing mounted on bed plates, a pair of upper knife holder drives mounted on said outer housing and adapted to drive an eccentric cam shaft journaled on said outer housing for lifting and lowering an upper knife holder, a shiftable inner shear housing moving parallel to the traveling stock, said inner housing being inside of said outer housing, guiding said liftable upper knife holder and carrying a lower knife holder to effect a shearing action between said upper knife holder, a pair of shifting supports bearing on said outer housing for supporting said inner shear housing, and a pair of shifting drives mounted on said bed plates for reciprocating said inner shear housing in synchronism with the traveling stock at the time of cutting; the improvement comprising inner and outer eccentric cam shafts and wherein the upper knife holder drives and the inside shearing housing reciprocating drives are driven separately by electric motors, and the upper knife holder drive motor is operated intermittently and the rotating speed of the eccentric cam shaft for the upper knife edge drive is rotated at a higher speed than the rotating speed of the inner and outer eccentric cam shafts for the inside shearing housing reciprocating flying drive.
